UNITED STATES PATENT OFFICE.

RALPH S. JENNINGS, OF BALTIMORE, MARYLAND.

BALE BAND AND TIE.

SPECIFICATION forming part of Letters Patent No. 238,910, dated March 15, 1881.

Application filed January 19, 1881. (No model.)

To all whom it may concern:

Be it known that I, RALPH S. JENNINGS, of Baltimore city, State of Maryland, have invented certain new and useful Improvements 5 in Bale Bands and Ties; and I hereby declare the same to be fully, clearly, and exactly described as follows, reference being had to the accompanying drawings, in which—

Figure 1 is a plan view of a part of the band, 10 portions of the same being broken away to show more fully its construction. Fig. 2 is a sectional view on line X X, Fig. 1. Fig. 3 is a sectional view of the band and tie, and Fig. 4 is a perspective view of the loop.

15 My invention has for its object to provide a substitute for the wrought-iron band and tie used on cotton-bales, dry-goods bales, and for analogous purposes, which shall be lighter, cheaper, and stronger than the iron band, and 20 more readily applied and removed.

To this end I construct the band of wood veneering in the direction of the length of the band, and combine therewith a tie adapted to 25 jam the ends of the band and effectively secure the same.

In the drawings, A is the band, composed, 30 by preference, of three layers of wood veneer, b c d, cemented together and having a covering, a, of burlaps or similar textile fabric or 35 strong paper cemented to the band. When using a single band, in order to render the wood tough and pliable, and not liable to split at the corners, where it is bent over the bale, I subject it to the action of superheated steam, 40 whereby the sap is driven out and the wood thoroughly dried, and then treat it with cotton-seed oil, glycerine, paraffine, or equivalent material mixed with a suitable diluent. The effect of this is to destroy the brittleness 45 of the wood and render it impervious to water. The wood is, by preference, sweet-gum, as the same grows in abundance throughout the southern States of the Union, and is tough and strong.

45 I am aware that bands or hoops consisting of a single strip of wood are old, and that tungstate of soda has long been known to possess fireproofing properties, and such I do not claim.

50 The tie is a simple cast or wrought iron clasp, D, whose inner sides are serrated or

roughened, as shown at e. In joining the ends of the band the same are thrust through the clasp D, and a wedge, B, is driven between the parts of the band, being, by preference, secured by means of a tack, C. The wedge jams the parts of the band tightly in the tie, where they are gripped by the serrations. The strain of the parts causes the tie to tend to tilt, as will be readily understood, increasing the grip 60 and effectually preventing the ends from slipping.

Such is the approved mode of constructing and applying the tie and band. Alternatives may be stated for both, as follows:

The band may be composed of any number of layers of veneer, and the textile fabric may be interposed between some or all of them, or may, if desired, be omitted altogether.

In using a single layer of veneer of wood, 70 the same may be covered with burlaps or textile fabric throughout its length, or it may be covered only at those portions which come opposite the corners of the bale, at which points a whipping of wire or cord may be used instead of the burlaps. The layers of veneer may be stitched either with cord or wire, preferably the latter, and in this case one layer of the veneer should have its grain crossing the band. The ends may be otherwise 75 connected, as by stitching or whipping with wire; or a different form of clamping-tie may be used. As stated, however, the described form is deemed the best.

What I claim is—

1. A composite veneer bale-band with a textile cover treated with tungstate of soda, whereby it is rendered fire-proof, as described.

2. In combination with the composite veneer band A, the wedge B, the clasp D, having interior serrated faces, adapted, as described, to tilt upon and secure the band, all as set forth.

3. A bale-band consisting of two or more sheets of veneer cemented together, and having a textile cover, a, cemented around the band, as set forth.

RALPH S. JENNINGS.
